US0D1109788S

(12) **United States Design Patent** (10) Patent No.: **US D1,109,788 S**
(Xu et al.) (45) Date of Patent: ** Jan. 20, 2026

(54) **SURVEILLANCE CAMERA**

(71) Applicant: **70mai Co., Ltd.**, Shanghai (CN)

(72) Inventors: **Qing Xu**, Shanghai (CN); **Hongjun Wang**, Shanghai (CN); **Xiaoxun Tang**, Shanghai (CN); **Yajie Tang**, Shanghai (CN); **Sheng Yang**, Shanghai (CN)

(73) Assignee: **70mai Co., Ltd.**, Shanghai (CN)

(**) Term: **15 Years**

(21) Appl. No.: **35/521,750**

(22) Filed: **Jul. 4, 2024**

(80) **Hague Agreement Data**

Int. Filing Date: **Jul. 4, 2024**

Int. Reg. No.: **DM/238512**

Int. Reg. Date: **Jul. 4, 2024**

Int. Reg. Pub. Date: **Jul. 26, 2024**

(30) **Foreign Application Priority Data**

Jun. 24, 2024 (CN) 202430389046.1

(51) **LOC (15) Cl.** **16-01**

(52) **U.S. Cl.**

USPC **D16/203**
